ROTARY MOTOR

Monte E. Hover, Culver City, Calif., assignor of
one-third to Daniel D. Evans and one-third to
Thomas Allen, both of Culver City, Calif.

Application October 10, 1935, Serial No. 44,436

8 Claims. (Cl. 123—11)

This invention relates to rotary motors, and while I show and shall hereinafter describe a form thereof designed especially to evolve kinetic energy by the spontaneous ignition of fuel in the power spaces of the motor, it is an object of the invention to design and construct the various parts employed so that by slight alteration, an external agent, such as the ignition system of an internal combustion engine, can be employed and 5 the motor operated by power evolved from timed explosions of gases in said spaces in the manner of an internal combustion engine.

An important object of the invention is to provide a rotary motor in which diametrically disposed pairs of opposed pistons will function in a highly reliable manner to insure complete scavenging of the working spaces between the pistons of all burned gases, thereby preventing loss of power.

Another object is to provide a rotary piston assembly consisting of diametrically disposed pairs of opposed pistons and means for accurately timing the relative movements of said opposed pistons with respect to the intake and exhaust 20 ports of the stator casing in which said pistons are mounted and for insuring operative timed injection of fuel between said pistons.

Another object is to provide a rotary motor, the rotary piston assembly of which is characterized by a novel association of diametrically disposed pairs of opposed pistons in which the pistons of each of said pairs define a working space therebetween, the form and construction of which will prevent fluid and compression 30 losses from said space during rotation of said assembly.

A further object is to provide a rotary motor having a rotary piston assembly constituting an inertia mass and including pairs of opposed, relatively movable pistons, actuation of which can be accurately controlled by power transferring means which automatically functions to determine operative co-ordination of the working spaces between the pistons with the air intake 40 and gas exhaust ports of the motor and which further insures the application of such relative movement of the pistons as is required to fully compress the air between the pistons in synchronization with the admission of the combustion spray.

With the above objects in view, the invention consists in the construction and combination of parts of which a preferred embodiment is illustrated in the accompanying drawings, wherein

Figure 1 is a vertical section through the motor with the pistons at the intake stroke;

Figures 2 to 5, inclusive, are more or less diagrammatic sectional views showing, respectively, different positions of the pistons in the 5 different cycles of operation of the motor;

Figure 6 is a vertical section through the motor cut on a line to show the piston assembly in elevation;

Figure 7 is a horizontal section through the 10 motor to fully disclose the working spaces between the opposed pistons of one of the pairs employed;

Figure 8 is a fragmentary vertical section through the motor illustrating the means for 15 timing operation of the fuel injector;

Figures 9 and 10 are perspective views of the respective piston elements of the piston assembly.

In carrying the invention into practice, use is made of a casing 5 having a cylindrical bore 6, 20 said casing having substantially diametrically disposed air intake ports 7 and substantially diametrically disposed exhaust ports 8, 8, in juxtaposition to the air intake ports. The casing is provided with suitable supply and exhaust conduits 9 for the respective ports 7 and 8.

Fixedly mounted at the ends of the bore 6 inwardly of the cylinder heads 11 are large herring-bone orbit or epicyclic gears 10 with each of which mesh small herring-bone driven planet gears 11a 30 on the crank shafts 11b, said gears 10 and 11a and said crank shafts providing means for timing operations of the co-operable pistons of the motor during planetary motion of the gears 11a.

Journalized to rotate in suitable bearings 12 35 upon the heads 11 is a driven shaft 13 and mounted upon said shaft is a rotary piston assembly consisting of relatively oscillatory piston elements 14 and 15, the former provided with substantially diametrically opposite pairs of cheek plates 40 16—16, the plates of each pair being connected together by a flat radial piston head 17, the latter functioning in practice the same as the end of a cylinder of the type having a reciprocable piston which is proportioned to provide a combustion space between the piston and said end. The element 15 is freely mounted on the shaft 13 and is provided with a pair of oppositely extending flat piston heads 18—18. The elements 14 and 15 are mounted on the shaft 13 so that 50 the heads 17 and 18 thereof are opposed to each other, the heads 18—18 being freely movable between the complementary cheek plates 16—16 of the element 14 and provided with packing strips 19 to bear against the inner faces of said plates. 55

The external diameter of the element 14 through the plane of the opposite pairs of cheek plates 16—16 is approximately equal to the diameter of the cylinder bore 6 and the arcuate edges 28 of said plates are provided with packing strips 21 which have close engagement with the wall of said bore. A like construction is provided for the outer edges of the piston heads 17 and the outer edges of the heads 18. The element 15 is formed 10 with a substantially cylindrical hub 22 over portions of which the inner wide width ends 23 of heads 17 may freely turn and against which the packing strips 24 of said ends are in fluid-sealed engagement. It is desirable to mention at this 15 point that the element 14 is keyed at 25 to the shaft 13 in order that the piston heads 17 of element 14 can oscillate relative to the opposed heads 18 of element 15.

The aforementioned crank shafts 11b are each 20 journaled for rotation in its complementary pair of cheek plates 16—16 of the element 14 and, as shown, each crank shaft has a pitman rod 26 connected with the confronting face of a respective piston head 18 of the element 15.

With the elements 14 and 15 in the correlated 25 positions shown in Figure 1 of the drawings, the crank shafts 11b are disposed parallel to the axis of the driven shaft 13, and these shafts, to which can be contributed the weight of the cheek 30 plates 16—16, function as an inertia and balancing mass. It also follows from the forms of 1 said elements 14 and 15 that the opposed pistons 17 and 18 co-act with the complementary cheek plates 16—16 and the internal annular wall of 35 the casing 5 to define fluid working chambers or spaces S, the outer ends of which are adapted to successively communicate with the intake and exhaust ports 7 and 8 at the respective sides of the casing 5, as clearly shown in Figures 1 to 5, inclusive, of the drawings in which views the motion 40 of the shaft 13 is clockwise. The port openings 7 and 8 are each characterized by parallel spaced apart portions 7a and 8a, as shown in Figure 6, and each represents an arc of a circle which is 45 concentric to the axis of the shaft 13. The inner surfaces of these ports form circumferential continuations of the bore 6 so that the end packing elements 17a and 18a of the pistons 17 and 18 can freely ride thereover.

In Figure 2, the pistons 17 and 18 are at the 50 instroke positions, at which time the fluid spaces S are in communication with the substantially diametrically opposite intake ports 7 for admission of air under pressure thereto from a suitable 55 source of supply (not shown).

In Figure 3, the pistons 17 and 18 are at the 60 compression stroke positions, during which time previously admitted air is being compressed between said pistons, it being understood that fuel 65 shall be injected into these spaces at the point of highest compression of the air and thus ignited following the theory of operation of such types of rotary motors.

In Figure 4 the positions of the pistons represent 65 the power stroke and in Figure 5 I have illustrated the positions of the pistons to exhaust the gases from the ports 8.

In each piston 17 is mounted an injector 27 in 70 the form of a cylinder having a reciprocal piston 28, the latter provided with a stem 29, movable through the head 30 of the cylinder and surrounded by a compression spring 31. One end of said spring bears against the head 30 and the opposite end against a flange 32 at the 75 outer end of the stem, whereby the pistons will be

urged to the full line positions shown in Figure 1. The injector cylinders 27 have nozzle portions 33 which open to the spaces S, whereby atomization of the spraying fluid can be effected and the spray discharged into the spaces. Fuel is introduced to the nozzle portions 33 through piping 34 past check valves 34a therein from the bore 35 of shaft 13, and, as shown, one end of the shaft has connection with a feed pipe 36, from a fuel source by means of which timed charges of 10 fuel can be passed to the bore 35 during operative timed movements of the pistons 17 and 18. Such feeding of fuel to the spaces S will be entirely according to "Diesel" engine practice and I make no claim to this feature. 15

In order that the fuel ejecting pistons 28 can be moved to fuel spraying positions in operative time with the compression strokes of the pistons 17 and 18, rocker arms 37 on the element 14 are employed, the same having knocker surfaces 38 bearing against the outer ends of the stems 29 and knocker surfaces 39, the latter adapted to be actuated by timing cams 40 on the inner face of an adjacent one of said heads 14, the cams being mounted for adjustment for operative timing of 25 the pistons 28.

Operation

Assuming that the motor has been started in operation in the manner common to this class 30 of motor, it follows that in response to actuation imparted to the piston assembly by the epicyclic gear train above described, air is drawn into the spaces S on clockwise movement of said assembly. As the relative motion of the pistons 17 and 18 35 changes periodically in timed response to power supplied by the motions of the cranks 11b and their pitman or connecting rods 26, the air thus admitted to the working spaces S will be highly compressed and thus become heated to a high 40 temperature; at the same time, a spray of oil will be injected into said spaces through the nozzles of cylinders 27 as is common in the "Diesel" type of motor. The oil thus ignites on meeting the air, and the resulting expansion of the fuel and air 45 mixture develops power sufficient to impart rotary motion to the shaft 13 to which the element 14 is keyed. After the power impulse has been imparted to the shaft 13 and as the piston assembly is rotated, relative motion of the pistons 50 towards each other causes the spaces S to be scavenged of combustion products through the exhaust ports 8 just previous to the admission of the next charge of air at the intake ports 7.

As I am particularly interested in the novel 55 assembly of pistons employed, the same timely functioning in the cycle to (1) admit air, (2) compress the air, and (3) admit a charge of fuel to the spaces S between the pistons 17 and 18, I have omitted from the accompanying drawings 60 any showing of means for cooling the cylinder and the pistons of the motor as this is well within the skill of persons trained in the art and any suitable well known means can be provided.

I claim as my invention:

1. In a rotary motor of the class described, a cylindrical casing having a concentric power transferring shaft; a pair of relatively oscillatory compressing elements co-operating with the casing to form a working chamber and being supported by the shaft, one of which is keyed to the shaft and the other of which is free theron to move angularly relative to the keyed element, the elements having contact at their outer ends with the walls of the bore of the casing, the keyed 75

element having spaced apart cheek plates between which the other element is free to move and said other element having packing strips bearing against the inner faces of the cheek plates and means for timing movement of the elements angularly relative to each other as the shaft is rotated.

2. In a rotary motor of the class described, a cylindrical casing having a concentric power transferring shaft; a pair of relatively oscillatory compressing elements co-operating with the casing to form a working chamber and being supported by the shaft, one of which is keyed to the shaft and the other of which is free thereon to move angularly relative to the keyed element, the elements having contact at their outer ends with the walls of the bore of the casing, the keyed element having spaced apart cheek plates between which the other element is free to move and said other element having packing strips bearing against the inner faces of the cheek plates and means for timing movement of the elements angularly relative to each other as the shaft is rotated, said element moving means including an epicyclic gear train having a system of motion imparting crank shafts carried by one element and linkages between said shafts and the other element to effect timed angular movement of one element relative to the other as aforesaid.

3. In a rotary motor of the class described, a cylindrical casing having a concentric power transferring shaft; a pair of relatively oscillatory compressing elements co-operating with the casing to form a working chamber and being supported by the shaft, one of which is keyed to the shaft and the other is free thereon to move angularly relative to the keyed element, the elements having contact at their outer ends with the walls of the bore of the casing, the keyed element having spaced apart cheek plates between which the other element is free to move and said other element having packing strips bearing against the inner faces of the cheek plates and means for timing movement of one of the elements angularly relative to the other as the shaft is rotated; and fuel ejectors carried by one of the elements for spraying liquid fuel between both elements.

4. In a rotary motor, a cylindrical casing having intake and exhaust ports; a shaft journalized in the casing co-axially therewith; a rotary piston assembly including co-operable elements one of which is fixed to the shaft and the other freely oscillatable thereon; one of the elements having cheek plates between which the other element operates for co-action therewith and with the internal annular wall of the casing in defining a working chamber in the latter between the elements; means through which fuel can be conducted to said chamber; and means for oscillating one of the elements relative to the other element and in such timed relationship to rotary motion of said shaft, as to cause induction of air into said chamber through the intake port for mixing of fuel with the air and compression, ignition, and expansion of the mixture to apply torque to the shaft and then effect the discharge of the combustion products from the chamber through the exhaust port.

5. In a rotary motor, a cylindrical casing having intake and exhaust ports; a shaft journalized in the casing co-axially therewith; a rotary piston assembly including co-operable elements one of which is fixed to the shaft and the other freely oscillatable thereon; one of the elements hav-

ing cheek plates between which the other element operates for co-action therewith and with the internal annular wall of the casing in defining a working chamber in the latter between the elements; means through which fuel can be conducted to said chamber; a crankshaft journaled in the cheek plates and having a crank between the latter; a link connecting the crank with the other element; and means for driving the crankshaft to oscillate the rotor shaft in such timed relationship to rotary motion of the latter, as to cause induction of air into said chamber through the intake port for mixing of fuel with the air and compression, ignition, and expansion of the mixture to apply torque to the shaft and then effect the discharge of the combustion products from the chamber through the exhaust port.

6. In a rotary motor, a cylindrical casing having intake and exhaust ports; a shaft journalized in the casing co-axially therewith; a rotary piston assembly including co-operable elements one of which is fixed to the shaft and the other freely oscillatable thereon; one of the elements having cheek plates between which the other element operates for co-action therewith and with the internal annular wall of the casing in defining a working chamber in the latter between the elements; means through which fuel can be conducted to said chamber; a crankshaft journaled in the cheek plates and having a crank between the latter; a link connecting the crank with the other element; gears fixed to the crankshaft exteriorly of the cheek plates; and internal gears fixed to the casing and constantly meshing with the crankshaft gears so as to drive the crankshaft and oscillate said other element in such timed relationship to rotary motion of the rotor shaft as to cause induction of air into said chamber through the intake port for mixing of fuel with the air, and compression, ignition and expansion of the mixture to apply torque to the shaft and then effect the discharge of combustion products from the chamber through the exhaust port.

7. In a rotary motor, a cylindrical casing having intake and exhaust ports; a shaft journalized in the casing co-axially therewith; a rotary piston assembly including co-operable elements one of which is provided with diametrically opposed piston heads having cheek plates projecting therefrom and including alined spaced apart hubs fixed to the shaft; the other element including diametrically opposed piston heads having an intermediate hub freely mounted on the shaft between the cheek plates for co-action of the latter with the piston heads of the elements and with the internal annular surface of the casing in defining oppositely related working chambers; means for conducting fuel to said chambers; and means for oscillating the freely mounted element in such timed relationship to rotary motion of the shaft as to effect induction of air to said chambers through the intake ports for mixing with fuel, and expansion following ignition of the mixture so as to apply torque to the shaft and then discharge the combustion products from the chambers through the exhaust ports.

8. In a rotary motor, a cylindrical casing having intake and exhaust ports; a shaft journalized in the casing co-axially therewith; a rotary piston assembly including co-operable elements one of which is provided with diametrically opposed piston heads having cheek plates projecting therefrom and including alined spaced apart

- hubs fixed to the shaft; the other element including diametrically opposed piston heads having an intermediate hub freely mounted on the shaft between the cheek plates for co-action of the latter with the piston heads of the elements and with the internal annular surface of the casing in defining oppositely related working chambers; means for conducting fuel to said chambers; crankshafts journaled in the cheek plates and having cranks therebetween; links connecting the cranks with the piston heads of the freely mounted element; gears fixed to the crankshafts

exteriorly of the cheek plates; and internal gears fixed to the casing and constantly meshing with the aforesigned gears to drive the crankshafts and oscillate the freely mounted element in such timed relationship to rotary motion of the rotor shaft as to effect induction of air to said chambers through the intake ports for mixing with fuel, and expansion following ignition of the mixture so as to apply torque to the shaft and then discharge the combustion products from the chambers through the exhaust ports. 5

MONTE E. HOVER.
